CLAIM

The ornamental design for pressurized sprayer for paint, as shown and described.

DESCRIPTION

1. Pressurized sprayer for paint

Design 1 shows two perspective line drawings and six orthogonal line drawings of the ornamental design of a pressurized sprayer for paint, shading is used to represent contours of surfaces of the product: fig. 1.1 front perspective view, fig. 1.2 rear perspective view, fig. 1.3 left side view, fig. 1.4 right side view, fig. 1.5 rear view, fig. 1.6 front view, fig. 1.7 top plan view, fig. 1.8 bottom plan view.

1 Claim, 8 Drawing Sheets(56)
